UNITED STATES PATENT OFFICE.

WILLIAM FREDERICK HENEY, OF MONTREAL, QUEBEC, CANADA.

REIN-SUPPORT.

SPECIFICATION forming part of Letters Patent No. 357,826, dated February 15, 1887.

Application filed September 23, 1886. Serial No. 214,560. (No model.)

To all whom it may concern:

Be it known that I, WILLIAM FREDERICK HENEY, of the city of Montreal, in the district of Montreal and Province of Quebec, Canada, 5 have invented certain new and useful Improvements in Rein-Supports; and I do hereby declare that the following is a full, clear, and exact description of the same.

This invention, which is primarily adapted 10 for reins, but may be used with a martingale, or in any place where a moving strap passes over any part of the harness, has special reference to the rein-supports now in use and attached to the sides of the neck-strap, front of 15 the breast-collar, &c., in which inwardly-curved fingers, either approaching each other or overlapping, allow the rein or strap to be introduced and hold it in place.

The object of my invention is to so construct 20 these that the width of the opening between the finger ends may be varied, so as to allow of the introduction of either a flat or a round rein, or the withdrawal of a rein when twisted.

The invention may be briefly described as 25 consisting in forming the base-plate, on which the fingers are mounted, of strong spring-steel or of like material, which may be bent so as to force apart the ends of the fingers and open them sufficiently to allow a round rein to 30 be introduced or withdrawn as well as a flat one, or by so doing to facilitate the putting in place or taking out of the ordinary rein. When in its normal position, the opening between the fingers is of such width as to allow 35 no chance of the rein or strap slipping out. This spring may be inclosed within the covering of the neck-strap or breast-collar, or held in place by a cover-strip passing over it and attached to either, the fingers being secured 40 to the spring-back by rivets, clinching-nails, &c., passing through strip.

For full comprehension of the invention ref-

erence must be had to the annexed drawings, forming part of this specification, in which Figure 1 shows a sectional elevation of my 45 rein-support in its normal position, and Fig. 2 a similar view showing it opened up for the reception of the rein or strap.

Similar letters of reference indicate like parts.

A is the neck-strap or breast-collar, to which the support is fastened, B being the spring-back, to which the fingers C are secured in any desired way—such as by rivets *d d* passing through the cover-strip E, which is sewed 55 to the neck-strap or other portion of the harness.

Although I have described the back of my rein-support as composed of spring-steel, it will be obvious that it may be made of any 60 substance which will give a firm support, can be bent, and will return to its normal curve.

I am aware that Letters Patent for over-check-terrets, No. 244,458, have been granted to John Hudson on the 19th of July, 1881, 65 and also that Letters Patent No. 331,479 were granted on the 1st of December, 1885, to T. Desjardins, for reins; but in the first of these each finger of the support is separately connected to the neck-strap or headstall, and in 70 the latter each finger of the support has its base separately connected to the neck-strap, both of which forms I disclaim.

What I claim is as follows:

As an improved article of manufacture, a 75 rein or strap support consisting of the two bent fingers secured to a single spring base-plate attached to the strap, as and for the purposes described.

WILLIAM FREDERICK HENEY.
